UNITED STATES PATENT OFFICE

2,434,534

MULTIPLEX JACK AND PLUG

William H. Alford, Winston-Salem, N. C.

Application December 29, 1945, Serial No. 637,932

4 Claims. (Cl. 173—328)

1

My invention relates to improvements in multiplex jack and plug construction, and more particularly to a plug provided with a plurality of insulated contact arms which are electrically connected to a terminal strip mounted in the end of the plug, said plug being adapted to be pushed into a cooperating jack provided with a plurality of contacts, whereby various circuits may be opened or closed as desired, said plug and jack further having means incorporated therein for a counter wheel so that preselected designated circuits may be opened or closed and the distance the plug is pushed into the jack to effect this operation will be indicated on the counter wheel.

An object of my invention is to provide an improved multiplex jack and plug equipped with a counter operated by the movement of the plug into the jack, whereby a visual indication will be given to show the desired or preselected distance the plug enters the jack in effecting the closing or opening of preselected circuits connected with the plug and jack.

Another object of my invention, in addition to the provision of a counter equipped plug and jack, is the utilization of a ball stop for holding the plug in the jack at any desired position to open or close the preselected or desired circuits.

A further object is to provide the jack with one or more sets of leaf contacts or switches, whereby exterior or additional circuits may be opened or closed, prior to the functioning of the switch mechanisms in the jack and plug.

Other objects will appear as the description proceeds.

In the accompanying drawings which form a part of my application:

Figure 1 is a combined view of the jack and plug spaced from each other, with parts shown in section.

Figure 2 is a transverse sectional view taken on the line 2—2 of Figure 1.

Figure 3 is a transverse sectional view taken on the line 3—3 of Figure 1, with sets of leaf switches shown at the opposite sides of the jack.

Figure 4 is a longitudinal sectional view taken through the plug, with one contact being shown as a modification and being connected to the terminal strip in the plug.

Figure 5 is a plan view of my improved jack showing the counter disposed on top thereof.

Figure 6 is an end view of the jack.

Figure 7 is a sectional view of the modified form of insulated contact, and

Figure 8 is a front view of the indicia strip used on the counter mechanism.

Like characters of reference are used throughout the following specification and the accompanying drawings to designate corresponding parts.

2

In carrying out my invention, I provide an improved form of jack 1 and cooperating removable plug 2, which may be made from any suitable material, although metal is found to be the desired material.

The jack 1, as clearly illustrated in Figures 1, 2 and 3 comprises an elongated housing, which is substantially square in cross section and is formed with a longitudinally extending bore 3. A spring tensioned plug locking ball 4 is carried at the front end of the jack and extends into the bore 3, and cooperates with circular grooves formed in the plug, later to be described. A plurality of oppositely disposed spaced grooves 5 are cut in the opposite sides of the bore 3, and are connected by the longitudinally extending oppositely disposed connecting grooves 6; whereby the contact arms on the plug later to be described, may be moved inwardly into the jack and turned clockwise or counter clockwise to contact the contacts 7 positioned at the ends of the grooves 5, said contacts 7 being connected by suitable wiring 8 to the desired circuits which are to be controlled.

The counter mechanism supported on the front end of the jack includes a cog wheel 9 and cooperating reduction gearing 10, which in turn is geared to the gear 11 on the shaft 12 upon which the indicia wheel 13 is mounted for rotation. An aperture 14 is formed in the counter casing where the number bearing indicia strip 13' on the wheel 13 may be viewed.

The plug 2 is shown in section in Figure 4, and comprises an elongated hollow body member formed of any desired insulating material and having an outer shell 15 of metal. A plurality of oppositely extending contact arms 16 are threaded into the insulating collars 17 in the plug 2 and the inner ends of the arms 16 engage the contact fingers 18 secured by rivets 19 in the plug 2. Suitable insulated electric wires will connect the contact fingers 18 with the terminal strip 20 carried at the forward end of the plug 1, and wiring (not shown) from the circuits to be controlled will be connected likewise with the said terminal strip 20. The forward end of the plug 2 is threaded to receive a removable protector cap 21, which is formed with an aperture 22 through which wires from the circuits to the terminal strip will pass. A slight modification of the contact fingers is shown in Figure 4, and in detail in Figure 7, and includes an internally threaded metal ferrule 23 which is pressed into an insulating ferrule 24, which in turn is pressed into the plug 2.

If desired, one or more leaf switches 25 may be secured to the opposite sides of the jack 1, each having an operating pin 26 extending from the switch to the spaced grooves 5, where the contact arms 16 will engage the ends of the pins 26 to operate the switches 25 prior to the arms 16 engaging the contacts 7 in the ends of the grooves

5, which later action causes other circuits to be made or broken.

The plug 2 is notched on its upper surface to form the track 27, which cooperates with and engages the cog wheel 9, so that movement of the plug into the jack causes the rotation of the counter mechanism to indicate the relative position of the plug to the jack and accordingly just what predetermined selected circuits are being opened or closed. A plurality of transverse locking grooves 28 are formed in the lower surface of the plug 2 and are positioned at spaced intervals between the laterally extending contact arms 16, and cooperate with the spring pressed plug locking ball 4 to hold the plug in the jack at the desired position.

From the foregoing description, it will be apparent that the plug 2 will be pushed into the jack a predetermined amount to cause the opening or closing of the desired circuits, and in pushing the plug in the jack, the counter will automatically indicate the position of the plug with respect to the jack, and accordingly, what circuits are being effected. Moreover, it will be understood that the plug will be rotated clockwise or counter clockwise to open or close the circuits by bringing the contact arms 16 into engagement with the contacts 7 supported in the grooves 5 in the jack 1.

It will be understood that I do not intend to limit myself to the exact construction illustrated in the drawings and described in the specification, as many minor changes in details of construction may be resorted to without departure from the spirit of the invention.

Having thus described my invention, what I claim as new and desire to secure by Letters Patent of the United States is:

1. A combined multiplex jack and plug comprising an elongated jack housing formed with a longitudinally extending cylindrical bore and diametrically opposed elongated arcuate slots at the opposite sides of said cylindrical bore merging therewith, longitudinally spaced contacts supported along the opposite ends of said slots, connections leading from said contacts exteriorly of said jack housing, said jack housing being formed with a radially extending slot disposed between said cylindrical bore and the outer surface of said jack housing, a cog wheel mounted transversely of said radial slot extending into said cylindrical bore, a counter supported upon said jack housing overlying said cog wheel and operatively connected therewith, an elongated hollow plug having diametrically opposed rows of radially extending spaced longitudinally disposed detachable contact arms and a longitudinally extending cog track intermediate the rows of contacts engageable with said cog wheel when said plug is inserted in said jack housing to indicate the various circuits which are opened or closed as said plug is inserted to various positions within said jack housing.

2. A combined multiplex jack and plug comprising an elongated jack housing formed with a longitudinally extending cylindrical bore and diametrically opposed elongated arcuate slots at the opposite sides of said cylindrical bore merging therewith, longitudinally spaced contacts supported along the opposite ends of said slots, connections leading from said contacts exteriorly of said jack housing, said jack housing being formed with a radially extending slot disposed between said cylindrical bore and the outer surface of said jack housing, a cog wheel mounted

transversely of said radial slot extending into said cylindrical bore, a counter supported upon said jack housing overlying said cog wheel and operatively connected therewith, an elongated hollow plug having diametrically opposed rows of radially extending spaced longitudinally disposed detachable contact arms and a longitudinally extending cog track intermediate the rows of contacts engageable with said cog wheel when said plug is inserted in said jack housing to indicate the various circuits which are opened or closed as said plug is inserted to various positions within said jack housing, a removable protector cap threaded upon the end of said plug, and a terminal strip formed integrally with said plug within said protector cap for supporting conductors connectible with the rows of spaced contacts on said plug.

3. A combined multiplex jack and plug comprising an elongated jack housing formed with a longitudinally extending cylindrical bore and diametrically opposed elongated arcuate slots at the opposite sides of said cylindrical bore merging therewith, longitudinally spaced contacts supported along the opposite ends of said slots, connections leading from said contacts exteriorly of said jack housing, said jack housing being formed with a radially extending slot disposed between said cylindrical bore and the outer surface of said jack housing, a cog wheel mounted transversely of said radial slot extending into said cylindrical bore, a counter supported upon said jack housing overlying said cog wheel and operatively connected therewith, an elongated hollow plug having diametrically opposed rows of radially extending spaced longitudinally disposed detachable contact arms and a longitudinally extending cog track intermediate the rows of contacts engageable with said cog wheel when said plug is inserted in said jack housing to indicate the various circuits which are opened or closed as said plug is inserted to various positions within said jack housing, a removable protector cap threadable upon the end of said plug, a terminal strip formed integral with said plug within said protector cap, and spaced contact fingers secured to the inner wall of said plug for supporting conductors connectible with said terminal strip.

4. The subject matter as claimed in claim 3, and concentrically arranged conducting and insulating bushings disposed within said plug for supporting said detachable contact arms.

WILLIAM H. ALFORD.
